UNITED STATES PATENT OFFICE

129,265

DESIGN FOR A FINGER BOWL OR SIMILAR ARTICLE

Thad Wilson, Gary, Ind.

Application June 21, 1941, Serial No. 101,610

Term of patent 14 years

To all whom it may concern:

Be it known that I, Thad Wilson, a citizen of the United States, residing at Gary, in the county of Lake and State of Indiana, have invented a new, original, and ornamental Design for a Finger Bowl or Similar Article, of which the following is a specification, reference being had to the accompanying drawing, forming part thereof.

In the drawing: Figure 1 is a top plan view of a finger bowl or similar article, showing my new design; Figure 2 is a side elevational view; and Figure 3 is an end elevational view thereof.

I claim:

The ornamental design for a finger bowl or similar article, as shown.

THAD WILSON.
